UNITED STATES PATENT OFFICE.

WILLIAM K. BOOTH, OF CHICAGO, ILLINOIS, ASSIGNOR TO BOOTH-HALL COMPANY, OF CHICAGO, ILLINOIS, A CORPORATION OF ILLINOIS.

ELECTRIC FURNACE.

1,299,110.

Specification of Letters Patent. Patented Apr. 1, 1919.

Application filed April 4, 1918. Serial No. 226,589.

To all whom it may concern:

Be it known that I, WILLIAM K. BOOTH, a citizen of the United States, residing at Chicago, in the county of Cook and State of Illinois, have invented a new and useful Improvement in Electric Furnaces, of which the following is a specification.

This invention relates particularly to electric furnaces equipped with wall terminals, or wall-contacts, adapted to co-act with electrodes which extend into the heating or fusing chamber of the furnace, as shown, for instance, in United States Letters Patent to William K. Booth, No. 1,244,415, granted October 23, 1917.

The primary object of the present invention is to provide an improved furnace construction of this type, provided with an improved wall terminal or terminals.

The invention is illustrated in its preferred embodiment in the accompanying drawings in which—

Figure 1 represents a plan sectional view of a furnace constructed in accordance with the invention, the section being taken approximately as indicated at line 1—1 of Fig. 6; Fig. 2, a broken sectional view taken as indicated at line 2 of Fig. 1; Fig. 3, a sectional view taken as indicated at line 3 of Fig. 1, showing the cross-section of the shank of the skeleton grid employed at the point where the section is taken; Fig. 4, a sectional view of the shank of the grid taken at line 4 of Fig. 1; Fig. 5, a sectional view taken as indicated at line 5 of Fig. 1 and showing a portion of a radiator attached to the shank of the grid; Fig. 6, a broken vertical sectional view of the furnace taken at line 6 of Fig. 1; and Fig. 7, a broken vertical sectional view taken as indicated at line 7 of Fig. 1.

In the preferred construction, which is illustrated, A represents the body of a furnace; B and B¹ wall-contacts, or wall terminals embedded in the bottom or hearth of the furnace; C and C¹ pairs of grids forming a portion of the wall terminal B; and D and D¹, pairs of grids forming a portion of the wall-contact B¹.

The furnace-body A preferably comprises the usual steel shell 1 provided with a re-

fractory lining 2, in the bottom of which are embedded the wall-contacts B and B¹. In the bottom of the shell is a layer 3 of highly refractory material, and between the wall-contacts B and B¹ is a central wall or bridge 3^a of the same material. The inner lining 3^b of the bottom is of the same highly refractory material, and affords facings for the wall-contacts B and B¹, which facings become conductive when heated. The portions 3, 3^a and 3^b of the bottom wall form a part of the lining 2 of the furnace. The shell 1 may be lined with refractory bricks 2^b, and the remainder of the refractory lining may be molded in place if desired, and fused under the action of the electric arc to form a monolithic mass.

Each of the wall-contacts B and B¹ preferably comprises a metal grid or grids embedded in conductive material of the second class.

If desired, one may take a mixture of refractory material or materials, which are non-conductive when cold, and carbon powder, with a suitable binder, so as to compactly fill the spaces or chambers which accommodate the wall-contacts, the mixture also being compacted in the interstices of the grids. The use of such a mixture is known in the art, but such a mixture may be used in connection with the improved grids herein shown.

It is preferred, however, to form the bodies of the wall-contacts of a metal carbide, employing the method fully described and claimed in my co-pending application No. 226,588 filed of even date herewith. Following is a description of the method of forming an acid furnace, which constitutes a modification of the construction claimed in my co-pending application mentioned.

According to this method, the portions 3, 3^a and 3^b of the lining of the bottom of the furnace are composed of silica which is fused by means of the electric arc to form a monolithic mass. The layer 3 may first be formed, and a layer of brick may be placed in the space which is to be occupied by the intermediate wall 3^a. I then take a mixture of silica, carbon-powder, and a suitable binder, such as coal-tar, mixed hot, and

place a layer of said mixture in the bottom of the space which is to be occupied by the wall-contact, place the grid or grids in position, cover them with a layer of the mixture to a depth of several inches, tamp the mixture down, and then subject the mixture to the fusing action of an electric arc from above, which will cause a reaction in accordance with the following formulæ:

The temperature should be between 1500° and 2000° C. At this temperature the reactions noted take place, assuming an excess of carbon to be present in the mixture. One may use about 60 per cent. silica, 40 per cent. carbon, and just enough coal-tar or hard-roofing-pitch to afford a suitable binder to enable the mixture to be tamped in place and hold its form until subjected to the fusing action of the electric arc. In this action, the silicon is set free and instantly unites with the carbon, forming silicon carbid which cools as a hard monolithic mass or matrix, holding the excess carbon and any refractory impurities which may be present. After the first layer of silicon carbid is formed, successive layers of the mixture adapted to form the carbid may be tamped in place and subjected to the action of the electric arc to convert the silicon to a carbid, which carries the excess carbon. These masses are welded together, forming virtually a single monolithic mass. As the operation progresses, and preferably before the carbid terminals have been formed, the central bricks may be removed and the space filled with silica, which may be fused by means of the electric arc, thus building up the central wall 3^a, layer by layer, if desired. After this wall is built, layers of silica are sintered or fused in place to form the lining 3^b, which will become conductive when hot. In the operation of fusing the materials forming the lining 3^b, this lining becomes welded or united to the carbid layer beneath, as well as to the bridge 3^a, so that the whole hearth of the furnace constitutes virtually an integral monolithic mass in which the grids are embedded.

In Fig. 6, E represent electrodes which depend into the fusing-chamber of the furnace and co-act with the wall-contacts embedded in the hearth. The furnace may be preliminarily heated to render the facings 3^b of the wall-contacts conductive in any suitable manner, as for instance, by employing an auxiliary electrode to co-operate with the main electrodes E in the manner described in the above mentioned patent.

There are four pairs of grids shown in Fig. 1, two pairs forming a part of the wall-contact B and two pairs forming a part

of the wall-contact B¹. Each pair is like the others, so that a description of one pair will apply to the others. The pair of grids C comprises complementary grids 4 and 5, having shanks 4^a and 5^a, which are firmly united together by means of bolts 6. The grids may be of any suitable metal, such as steel, iron or copper. Each grid is of skeleton construction, and preferably comprises thin bars which are united by other bars extending at an angle to the first mentioned bars. Thus the grid 4 comprises bars 4^b united by bars 4^c, the bars 4^c being extended and united with the shank 4^a. Similarly the grid 5 comprises bars 5^b united by bars 5^c, the bars 5^c being extended and united with the shank 5^a. The cross-section of the shanks 4^a and 5^a is formed with a view to avoiding the use of large or heavy masses of metal, with a view to overcoming objectionable hysteresis and reactance and skin effects. Thus, the cross-sections of the shanks taken as indicated by the arrows at the lines 2, 3 and 4 of Fig. 1, are shown in Figs. 2, 3 and 4. The shanks of each pair of grids are united by the bolts 6, as shown. The bolts which are near the outer ends of the shanks serve to connect with the shanks the metal-conducting bars 7 which connect with the bus-bars or conductors 7^a, which connect the shanks of the grids on each side of the furnace, as will be understood from Fig. 1. The bus-bar 7^a at one side of the furnace connects with a conductor 8, which may lead to an auxiliary electrode, and also connects with a conductor 9, which forms a part of the external circuit 10, and which may connect, for instance, with the secondary circuit of transformer means. The bus-bar 7^a at the opposite side of the furnace is shown supported by insulators 11. The circuits of this furnace may be arranged, if desired, in accordance with the circuits shown in Fig. 2 of the patent mentioned above, in which case an auxiliary electrode would be supplied for use in preliminarily heating the furnace, in the manner described in said patent.

The shank of each grid is equipped at its outer end with a radiator 12, which comprises a fin 12^a equipped at its opposite sides with radiating ribs 12^b. A section through the radiator is shown in Fig. 5. The purpose is to cool the shanks by radiating heat to the air, thus rendering it unnecessary to water-cool the grids.

It will be noted that the grids are preferably disposed near the outer portion of the bottom wall of the furnace, so that the grids are protected from the heat in the furnace by the carbid blocks B and B¹ and the highly refractory facings 3^b of said blocks. The grids are adapted to make intimate contact with the carbid blocks, and because of

the comparatively small cross-section of the grid at any point, objectionable hysteresis and reactance and skin effects are avoided where alternating currents are employed.

5. The silicon carbide block affords a comparatively good conductor of electricity, and is highly resistant to disintegration, especially when protected by the facings 3^b of silica. In case the facings 3^b are partially destroyed, the improved wall-contacts which preferably carry a considerable amount of free carbon, still offer resistance to disintegration by heat, and will give up less carbon to the metal bath in the furnace than would a pure carbon block, for instance, when employed as a wall-contact.

While it is preferred, ordinarily, to employ a facing of silica or other highly refractory material of acid character, in connection with the wall-contact, in some cases the facing of silica may be dispensed with.

If desired, the metal grid may be protected by a suitable coating or jacket of carbon to prevent fusing or disintegration of the grid when the carbide is being formed. This may be accomplished, for illustration, by dipping the grid in melted tar containing free carbon, or in melted tar and then into carbon powder which will adhere to the tar. 30 If a portion of the grid combines with carbon, this will cause no serious defects so long as sufficient metal is preserved to maintain the mechanical strength of the grid and avoid breakage, moreover, a sufficiently deep 35 layer of the carbide-forming material may be placed above the grid to protect it from fusing, as it is not essential that these materials within the interstices of the grid should be converted to carbide.

40. It may be remarked that the formation of the grids is such as not only to avoid reactance, hysteresis and skin effects, but, also, the grids present a very large area of contact to the conductive body in which they are embedded, thereby avoiding injurious local heating and loss of efficiency in the electric circuit.

The foregoing detailed description has been given for clearness of understanding 50 only, and no unnecessary limitation should be understood therefrom, but the appended claims should be construed as broadly as permissible in view of the prior art.

What I regard as new and desire to secure 55 by Letters Patent is—

1. In an electric furnace, a wall-contact comprising a skeleton grid and conductive refractory material in which said grid is embedded.

60. 2. In an electric furnace, a wall-contact comprising a skeleton grid and a block of refractory conductive material in which said grid is embedded, said grid having a shank adapted to extend through a wall of the fur-

nace and connect with the external circuit of 65 the furnace.

3. In an electric furnace, a wall-contact comprising a body of refractory conductive material, and a pair of complementary skeleton grids embedded in said body and having 70 shanks disposed together and extending through a wall of the furnace.

4. The combination with a furnace provided with a refractory wall, of an open-work metal grid having a shank extending 75 through said wall, said grid and shank being composed of sections of small area.

5. The combination with a furnace having a refractory wall, of a grid comprising bars and a laminated shank extending 80 through said wall, and a block of conductive refractory material in which said grid is embedded.

6. In an electric furnace, a wall-contact comprising a body of conductive refractory 85 material, and a member embedded therein and having a shank extending through the furnace-wall and equipped with an air radiator.

7. The combination with a furnace-body 90 having a refractory wall, of a wall-contact comprising silicon carbide forming a monolithic mass.

8. The combination with a furnace-body 95 having a refractory wall, of a wall-contact comprising silicon carbide forming a monolithic matrix and a refractory conductive material in said matrix.

9. In an electric furnace, a wall-contact comprising silicon carbide forming a hard 100 matrix, and a facing of silica.

10. In an electric furnace, a wall-contact comprising a hard mass of silicon carbide forming a matrix, carbon carried in said matrix, and a facing of silica. 105

11. In an electric furnace, a wall-contact comprising a hard mass of silicon carbide, a grid embedded therein and having a shank adapted to extend through the furnace-wall, and a hard refractory facing forming the 110 inner lining of the wall-contact, which becomes conductive when heated, said lining being of an acid character.

12. The method of forming an acid hearth, which consists in mixing materials adapted 115 to react and form a silicon carbide, and subjecting the mixture to a temperature sufficient to effect reaction and form a monolithic mass.

13. The method of forming a wall-contact for an acid furnace, which consists in placing in a bed in the furnace-wall a mixture of materials adapted to react to produce silicon carbide, and subjecting the mixture, *in situ*, to a temperature sufficient to effect reaction and form a monolithic mass. 120

14. The method of forming an acid furnace wall-contact, which consists in mixing 125

materials comprising silica and carbon, and subjecting the mixture to a temperature in excess of 1500° C. in such manner as to cause reaction and form silicon carbide in a monolithic mass.

15. The method of forming an acid furnace with a wall-contact, which consists in

mixing silica and carbonaceous material in quantities sufficient to furnish an excess of carbon, and subjecting the materials to the action of an electric arc at such a temperature as to form silicon carbide in a monolithic mass as a matrix carrying the excess carbon.

WILLIAM K. BOOTH.
